UNITED STATES PATENT OFFICE.

FRANK JOHANNESSEN, OF ERIE, PENNSYLVANIA, ASSIGNOR TO MERGENTHALER LINOTYPE COMPANY, A CORPORATION OF NEW YORK.

LINOTYPE-MACHINE.

939,262.

Specification of Letters Patent.

Patented Nov. 9, 1909.

Application filed April 8, 1908. Serial No. 425,920.

To all whom it may concern:

Be it known that I, FRANK JOHANNESSEN, of Erie, county of Erie, and State of Pennsylvania, have invented a new and useful Improvement in Linotype-Machines, of which the following is a specification.

My invention has reference to that class of machines in which slugs or bars, bearing on one edge the characters to print an entire line, are cast in a slotted mold against a composed line of matrices presented temporarily thereto.

It is intended more particularly for use in those machines in which the mold is carried by an intermittently rotated disk, by which it is presented alternately at the casting position and the position to permit ejection of the slug.

The aim of the invention is to provide the instantaneous and accurate adjustment of the mold slot so that it may be caused to produce slugs of any length or thickness demanded. The mold consists mainly of a body portion and a parallel cap portion, between which the slot or mold proper exists, the distance between them being variable to change the thickness of the slugs produced; and of a series of independently movable transverse slides or liners to close the mold slot at one end, thereby reducing its length and the length of the slugs produced.

I combine with the above parts, which are mounted on the rotating disk, manually controllable mechanism by which the number of liners in use may be controlled to regulate the length of the slug, and by which the distance of the cap from the body may be controlled to vary the thickness, each of these adjustments being independent of the other, so that the slugs may be varied either in length or in thickness, or in both.

I also provide means for adjusting the jaw for confining the matrix line and connect the same with the mold-adjusting devices so that the adjustment of the mold to a given length will be accompanied by an adjustment of the jaw to confine a matrix line of equal length.

I also connect the mechanism for adjusting the width of the mold slot with means for adjusting the slug-trimming knives, so that the latter are automatically adjusted to correspond with the thickness of the slugs produced by the mold. The manual devices for effecting the adjustments, are mounted

on the main-frame and arranged to co-operate with a mold and its adjuncts on the rotary disk when required.

In the drawings,—Figure 1 is a front elevation of the mold-carrying disk and adjacent parts, portions being broken away to show the internal construction. Fig. 2 is a horizontal central section of the parts shown in the preceding figure. Fig. 2^A is a section on the same plane as Fig. 2, but with the liners disconnected from the actuating slide. Fig. 2^B is a rear elevation of the series of liners, with the vertical rack-bar by which they are thrown into and out of engagement with their actuating slide. Fig. 3 is a face view of the main slide for throwing the selected liners into and out of action. Fig. 4 is a horizontal section of the same on the line 4—4, Fig. 3. Fig. 5 is a vertical section on the line 5—5, Fig. 3. Fig. 6 is a perspective view of detached parts.

Referring to the drawings, A represents the vertical intermittently rotated disk, in which the mold mechanism is carried, this disk being provided on the outer edge with gear teeth through which it receives motion, as usual.

B is the central horizontal shaft on which the disk is supported.

C is a horizontal sleeve sustaining the shaft and forming part of a horizontal slide which is moved forward and backward in the main-frame, as usual, in order to move the disk A and the mold therein facewise to and from the matrix line in a manner well understood in the art.

D' and D² are two parallel plates rigidly secured to the disk and forming the body portion of the mold.

E, E, are a series of parallel liners arranged to slide independently transversely of the mold body, with their outer ends flattened so that they may be drawn back to a common plane to serve jointly as one side or wall of the mold slot. Any number of these slides may be advanced beyond the others across the mold slot to reduce its length, as will be hereinafter more fully explained.

F is a mold cap having a flat face lying parallel with the ends of the liners and forming one wall of the slot or mold proper G, in which the slug is cast.

H, H, are two rigid plates extending beyond the body of the mold, and forming the

ends of the mold slot when it is adjusted to its maximum length. These end plates H are grooved and serve as guides for the mold cap F, which is movable to and from the ends of the retracted liners in order to vary the width of the slot and the thickness of the slugs produced, in a manner which will be hereinafter explained. When all of the liners are retracted toward the body portion, a slug of maximum length may be cast, extending across the ends of the entire series of liners from one of the end plates H to the other. Any number of the liners, which are of an em pica in thickness, or of any other desired thickness, may be advanced endwise against the cap, beginning at one end of the mold, the effect of each liner being to reduce the length of the mold slot an amount equal to the thickness of the liner. In other words, the advance of each liner will reduce the mold and the resulting slugs one em in length, so that a slot for slugs of any length may be produced by simply advancing the required number of liners.

In order that the operator may instantly adjust the mold for a slug of any given measure by advancing the requisite number of liners, I provide the following mechanism.

I mount in guides on the mold disk, a sliding plate I, movable forward and backward lengthwise of the liners, or in other words toward and from the mold cap F, and on this plate I mount a stud i extending into a cam groove i' in the non-rotating sleeve C, so that each time the mold disk A is revolved, the cam causes the slide I to move backward or inward radially on the disk. Between disk A and slide I, I seat spiral springs i¹⁰ (Figs. 1 and 3), bearing at opposite ends against said parts respectively, for the purpose of urging the plate endwise on the disk toward the mold cap F. Each of the liners E is jointed vertically midway of its length at e, and its rear end e' is formed on opposite sides with vertical shoulders e² and e³. The slide I is provided, Figs. 2, 2^A, 3 and 4, with a plate or shoulder i⁴ to act against the rear ends of the liners and push them forward against the mold cap F, and it is also provided with a shoulder i⁵ to effect the retraction of the liners when their rear ends e' are shifted to engage therewith. Comb-springs i⁶, attached to the slide I, act against the rear ends of the liners and tend to throw them laterally out of the path of the shoulders i⁴ and i⁵, as shown in Fig. 2^A. Whenever one of these springs is permitted to act, the corresponding liner in the retracted position has its end e' thrown sidewise so as to engage behind the body D', as shown in Fig. 2^A. In this position, the end of the liner is beyond the path of the shoulders on

the slide I, so that although the slide may be carried forward, the liner will be permitted to remain at rest in its backward position. Thus it will be seen, the advancing slide serves to push forward across the mold slot only those liners whose rear ends have been pressed sidewise into the path of the shoulder i⁴.

In order to determine the number of liners which will be advanced across the slot, I provide a vertically sliding rack-bar J beveled at the upper end, as shown in Fig. 2^B, mounted in the mold body and adapted to ride across the ends of the liners on one side and press them backward laterally and successively in position to be acted upon by the pusher slide I. This rack-bar, shown in detail in Fig. 2^A, is adjusted by a gear K, mounted to turn loosely on the shaft B of the mold disk, and receiving motion in turn from an idle gear L mounted on the mold disk, the arrangement being such that the parts will all rotate together and the selected number of liners remain in action until the adjustment is changed by the operator through parts located on the main frame.

For the purpose of effecting this adjustment while the mold disk is at rest, I provide the pinion M, designed to engage the idler L, and mounted on a horizontal shaft N, seated in the main-frame and provided at its forward end with a graduated index wheel O, adapted to be turned by hand.

The shaft N is movable endwise in its bearings, and is held normally forward by a spring n which keeps the gear M normally out of the path of the idle gear L. When, however, an adjustment is required, the operator, grasping the wheel O, pushes the shaft N rearward, carrying the gear M to engagement with the idler L, after which he rotates the wheel O, thereby moving the liner-controlling rack J upward or downward until it has pushed the required number of liners into position to be acted upon by the slide I. The wheel O has, as shown in Figs. 1 and 2, a flange o provided, as shown in Fig. 1 with graduations representing ems, and adapted to be read in connection with the fixed mark or pointer, so that the operator, to adjust the mold to the required length, has only to turn the wheel until the proper graduation alines with the pointer, after which, the shaft is permitted to slide forward to disengage the gear M. The mold disk stops, in the course of its rotation, in definite positions, as usual, and in order that the gear M may be certain to properly reengage the idler L, I provide for locking the gear M against accidental rotation. This is effected by providing its shaft N with a second pinion m adapted to engage a fixed locking plate m' when the shaft N moves forward.

The matrix line, when in the casting position before the mold, is confined, as usual in this class of machines, at one end by a horizontally sliding jaw P, which must be secured at a distance from the opposing jaw equal to the length of the mold and of the slugs produced therein. For the purpose of locking this jaw in its different positions, I provide a vertically guided plate Q, having on its upper surface a series of stops or shoulders q to engage and support the outer end of the jaw. By raising and lowering the plate, it may be caused to lock the jaw in any position, that is to say, for any length of line.

It is usual, after the casting action, to permit a slight backward motion of the jaw in order to release the confined line and permit the wedge-justifiers therein to fall to their normal positions. In order to permit this movement, I provide the locking plate Q with a vertical slot q' engaging a stud or its equivalent q² on a nut m², which receives a slight horizontal motion through a pinion m⁸ on its end, the pinion being in turn actuated by the mechanism of the machine. So far as this nut and its actuating devices are concerned, they are identical with those indicated by corresponding letters in U. S. Patent No. 436,581. This nut may be adjusted at will to move the jaw a distance less than the length of the teeth q. This permits the mold and the jaw to be adjusted to produce slugs of any length required between the regular or standard lengths.

In order to insure an adjustment of the jaw P corresponding to the adjustment of the mold as to length, I attach to the jaw a downwardly extending rack-bar R, which engages the pinion r on the mold-adjusting shaft N. When, therefore, this shaft is turned to regulate the length of the mold, it sets the plate Q at such height as to lock the jaw P in the required position. The essence of the invention in this regard consists in a mechanical connection between the means for determining the position of the jaw and the means for determining the length of the mold, and it will be manifest to the skilled mechanic that the parts may be widely varied in form and arrangement without departing from my invention.

I will now describe the means for adjusting the mold cap to vary the thickness of the slug. The mold cap is urged constantly away from the body and the liners by underlying springs f, seated in the body and is supported and urged toward the body against the influence of the springs by a vertically guided wedge bar f', seated at one side against the cap, and at the opposite side against the mold disk or other solid support. By moving this wedge-bar downward, the cap is crowded inward and the thickness of the mold slot and the slugs reduced accord-

ingly. When the wedge is moved in the opposite direction, the springs automatically force the cap outward to increase the width of the slot. The wedge f' is notched on one side and locked in its adjusted positions by a spring-actuated pawl f². The vertical movement of the wedge is effected by an arm s on the upper end of a rack-bar S actuated by a pinion s' on the end of a horizontal shaft s², which is provided at its forward extremity with a hand-wheel s", so that by turning this wheel, which is suitably graduated for the purpose of determining its adjustment, the mold may be adjusted to produce a slug of any thickness required.

As the mold revolves with the disk while the adjusting arm s and its connections are mounted on the main-frame, provision must be made for throwing the arm into engagement with wedge f' when the mold is to be adjusted, and out again after the adjustment has been effected. To this end the rack-bar S is mounted, as shown in Figs. 1 and 6, in a hand-lever T of angular form, having at the lower end the horizontal hole t² to receive a supporting axis on the main-frame. By swinging the lever T sidewise about said axis toward and from the edge of the mold disk A, the arm s may be thrown into engagement with the wedge f'. The lever is also provided at its upper end with one or more teeth t which engage the teeth of the disk in order to lock it firmly against rotation while the adjustment of the mold cap is taking place.

While the mold stands in the position shown, with its slot in a vertical position, the slugs are ejected therefrom and driven forward between two trimming knives U, U, one of which is adjustable by means of a vertical wedge u as usual. This wedge f' is also operated by the arm s. In other words, this arm operates simultaneously the wedge for adjusting the thickness of the mold slot and the wedge u for determining the adjustment of the knives. The arm engages and disengages the two wedges in like manner, the two ends of the arm being provided, as shown in Fig. 6, with horizontal slots s¹⁰ and s¹¹ to receive studs on the sides of the respective wedges. The knife-adjusting wedge is locked as usual, by a spring-actuated pin u'. Before the wedges can be moved, they must both be unlocked. For this purpose, I mount on the side of the hand-lever T a thumb-lever t' connected by a link t² with the slide t² mounted in the side of the main lever, and having lateral arms to engage the latch f² and the pin u'.

To effect the adjustment of the mold and knives, the main lever T is moved to engage and lock the mold disk and throw the arm s into engagement with the wedges, after which the secondary lever t' is actuated to unlock the wedges, which are then adjusted.

vertically by actuating the rack-bar S through the hand-wheel s², already referred to. It will be observed that the foregoing arrangement effects the simultaneous and corresponding adjustment of the mold and the knives.

It is to be noted that the liners are advanced toward and against the cap by spring connections, and that they follow the cap automatically to any position in which it may be placed.

Having thus described my invention, I claim and desire to secure by Letters Patent:

15. 1. In a mold for a line-casting machine, a cap portion, a series of liners movable transversely to the cap, spring-actuated means for advancing the liners against the cap, means for holding the liners away from the cap, and controllable means for determining the number of liners to be placed in each position; whereby the length of the mold slot may be varied at will.
20. 2. In a slotted mold for a line-casting machine, a cap portion and means for moving the same transversely of the slot to vary the thickness of the slug, in combination with a body portion, a series of liners slideable transversely of the slot, spring-actuated means for advancing the liners toward the cap, and controllable means for holding a predetermined number of liners away from the cap; whereby any desired number of liners may be caused to serve as one wall of the mold slot, and the remaining liners caused to limit the length of the slot.
25. 3. In combination, the mold cap, the mold body, the series of sliding liners, the reciprocating plate I adapted to advance and retract the liners, springs tending to disengage the liners from the plate, and controllable means whereby any desired number of liners may be connected with the plate.
30. 4. In combination with a revolving disk, a slotted mold secured thereto and including a series of sliding liners for changing the length of the slot, means for automatically operating said liners during the rotation of the disk, and controllable devices to vary the action of the automatic means; whereby the automatic mechanism may be caused to give the mold any predetermined length.
35. 5. In combination with a rotary disk, the slotted mold including the sliding liners, a sliding plate to advance and retract the liners, springs tending to advance said plate, a cam to effect its automatic retraction, and manually controllable means for determining the number of liners advanced.
40. 6. The rotary disk and the slotted mold secured thereto and including the sliding liners, in combination with the slide to advance and retract the liners, spring connections urging the slide in one direction, a

cam to move it in the opposite direction, a sliding rack to determine the number of liners advanced by the slide, and a rack-actuating mechanism consisting of a manually operated wheel on the main-frame, and rack-operating gears adapted to be operated thereby at will.

7. In combination with a rotary disk, the mold including the sliding liners, a slide to move the liners, the rack to determine the number of liners actuated by the slide, the intermediate gears K and L carried by the disk, and the manually operated gear M mounted in the main-frame and adapted to be engaged by the gear L.

8. A mold for a line-casting machine including the cap portion, the opposed liners with jointed rear ends, the reciprocating plate I adapted to advance and retract the liners, springs tending to move the jointed ends of the liners in one direction, and a slide adapted to move them in the opposite direction; whereby any desired number of liners may be connected to the operating plate.

9. In a slotted mold for a line-casting machine, a series of sliding liners to determine the length of the slot, spring mechanism for advancing the liners to shorten the slot, means for positively retracting the liners, means for determining the number of liners advanced, and means for locking back the liners which are not advanced; whereby any desired number of liners may be advanced to give the slot a predetermined length, while the remaining liners are locked back that their ends may serve as portions of the wall of the slot.

10. In a line-casting machine, a slotted mold containing a series of liners to vary the length of the slot, and a movable jaw to confine the matrix line, in combination with intermediate mechanism for determining the position of the jaw in relation to the number of liners in use.

11. In a line-casting machine, a slotted mold including a series of sliding liners for changing the length of the slot, a movable jaw to confine the matrix line, means for locking the jaw in different positions corresponding to the lengths of the mold slot, a manually operative member and connections through which it controls the liners and the jaw-locking devices; whereby the simultaneous and corresponding adjustment of the mold slot and the jaw is effected.

In testimony whereof I hereunto set my hand this twenty-second day of February, 1908, in the presence of two attesting witnesses.

FRANK JOHANNESEN.
